APPARATUS FOR FEEDING SPANGLES TO SPANGLING MACHINES

Filed Nov. 23, 1944

UNITED STATES PATENT OFFICE

2,400,616

APPARATUS FOR FEEDING SPANGLES TO
SPANGLING MACHINES

Charles Weiss, Corona, Long Island, N. Y., assignor to Joseph Brandt & Bro. Inc., New York, N. Y., a corporation of New York

Application November 23, 1944, Serial No. 564,747

10 Claims. (Cl. 223—48)

This invention relates to apparatus for producing threaded spangles and, more particularly, to means for feeding to the spangling machine the spangles together with a thread or string which is threaded through the apertures of the spangles.

Apparatus to which the present invention relates is disclosed in United States Patent to Brandt No. 2,327,957, granted August 24, 1943. As explained in said patent, the thread or string and the spangles carried thereby are moved downwardly to the spangling machine on an inclined support of considerable length. One of the objects of the present invention is to reduce to a considerable extent the amount of floor space required for feeding the spangles and the companion thread or string to the spangling machine.

Another object of the invention is to provide a thread and spangle feeding apparatus with means for positively advancing the thread and the spangles in the course of the travel of the thread and spangles from the supply spool to the spangling machine.

The above and other objects, features and advantages of the invention will be fully understood from the following description, reference being had to the accompanying illustrative drawing.

In the drawing:

Fig. 1 is a side view of the spangle and thread feeding apparatus embodying the present invention, said feeding apparatus being shown in association with a spangling machine illustrated more or less diagrammatically;

Fig. 2 is a top plan view of part of the feeding apparatus of the present invention;

Fig. 3 is a view, on a larger scale, of part of the apparatus on the line 3—3 of Fig. 1;

Fig. 4 is a top plan view of the lower part of the lower support.

As illustrated in the drawing, the spangle-feeding apparatus supplies the spangles 10 and the string 12, which is threaded through said spangles, from a spool 14 to a spangling machine 16, said supply spool being mounted in elevated position in respect to the intake of the spangling machine. It will be understood that string 12 carrying a multiplicity of the spangles 10 through which said string is threaded and on which said spangles move while being fed to the spangling machine is unwound from spool 14 while the thread and spangles travel to the spangling machine, said spool being provided with a suitable friction brake (not shown) to provide for the tensioning of the string while it is being unwound.

The feeding apparatus of the present invention comprises means for supporting the spangles 10 for movement toward the spangling

machine. Said supporting means comprises a lower downwardly inclined support in the form of a trough or ramp 18 and an upper downwardly inclined support in the form of a trough or ramp 20 which is positioned above trough 18. As illustrated in Fig. 1, trough 18 is inclined downwardly toward the spangling machine while upper trough 20, positioned above trough 18, is inclined downwardly toward the upper part of lower trough 18 from a point above the lower part of trough 18. Trough 18 comprises a bottom 22 and opposite side walls 24, and similarly trough 20 comprises a bottom 26 and opposite side walls 28. The lower downwardly inclined trough 18 is supported in any suitable way as by vertical supports 30 and 32, and the upper downwardly inclined trough 20 is supported by side members 34 and 36 secured to the opposite side walls of troughs 18 and 20. The spool 14 is mounted for rotation at the upper ends of vertical members 38 secured to said walls 28 of trough 20 at the upper end of the latter.

It will be understood that as the string 12 and the spangles 10 travel to the spangling machine they move downwardly from supply spool 14 to the lower end of trough 20 in a direction away from the spangling machine and then in the opposite direction down trough 18 toward the spangling machine. The means for reversing the direction of movement of string 12 and spangles 10 comprises a driven roller 40 positioned at the lower end of upper trough 20. More specifically, as here shown, said driven roller 40 is fixed to a shaft 42 which is journaled for rotation in bracket arms 44 secured to trough 20 at the lower end thereof. A pulley 46 is fixed to shaft 42 and is driven by a belt 48 which in turn is driven by a pulley 50 which is fixed to the driven shaft 52 which operates the roller 54 at the lower end of trough 18. Said shaft 52 is driven by a pulley 53 operated by a belt 55 driven at the proper speed by a part of the spangling machine as described in said Brandt patent. Belt 48, which drives pulley 46 for rotating roller 40, is crossed so that the roller 40 at the lower end of upper trough 20 rotates in a counter-clockwise direction while roller 54 at the lower part of trough 18 rotates in a clockwise direction (viewing Fig. 1). Thus, rollers 40 and 54 are driven in unison by belts 48 and 55 to advance the spangles toward the spangling machine. Roller 56 is driven by a pulley 57 operated by belt 59 driven by pulley 61 on shaft 52. From roller 54 the string 12 and the spangles 10 pass to and are engaged by the driven roller 56 which is provided with the string-raising member 58 which operates to raise the spangles 10 periodically above the barrier 60 of the feed control device illustrated in Fig. 3, which as here shown, is the same as that illustrated in

Fig. 3 of the above mentioned Brandt patent. It will be understood, however, that it is within the scope of the present invention to utilize means other than that herein specifically illustrated for periodically releasing the spangles for movement from the feeding apparatus to the guide chute 62 of the spangling machine.

It will be understood that as the spangles 10 move downwardly on string 12 from spool 14, said spangles are supported on the bottom of trough 20 and move downwardly on said trough bottom. Likewise, said spangles are supported by the bottom 22 of lower trough 18 while they move downwardly on said trough. As the spangles move downwardly on said troughs, they are retarded by the frictional engagement of said spangles with the trough bottoms and that the string 12 drawn from spool 14, while being fed into the spangling machine, moves in relation to the spangles on troughs 18 and 20. In this connection, it will be understood, that as explained in said Brandt patent, the length of string 12 is much greater than the combined thickness of all of the spangles initially mounted on said string.

It will be noted that roller 40 at the lower end of upper trough 20 not only serves to reverse the direction of movement of string 12 and spangles 10, but also aids in advancing said string and spangles and relieves string 12 from harmful tension so that said string is not required to move the spangles around roller 40. It will be understood further that by reason of the construction and arrangement of the feeding apparatus of the present invention, the required floor space is considerably reduced as compared with the floor space required for the feeding apparatus illustrated in the above mentioned patent to Brandt, while on the other hand, the advantages of the feeding apparatus shown in said patent are retained in the feeding apparatus of the present invention. Further, it will be understood that the apparatus shown in the accompanying drawing at the lower end of trough 18, beginning with roller 54 and including all of the parts of the apparatus at the right thereof, including spangling machine, are all as illustrated and described in said Brandt patent, except that roller shaft 52, which corresponds to the shaft of roller 60 of the apparatus illustrated in the Brandt patent, is provided with a pulley 50 for driving belt 48. Thus, it is seen that the apparatus illustrated in the Brandt patent can be readily adapted, pursuant to the present invention, to embody the principles and advantages of the present invention.

While I have shown and described the presently preferred embodiment of my invention in the form in which it is now being employed in connection with a spangling machine, it will be understood that various changes and adaptations may be made therein without departing from the invention within the scope of the appended claims.

Having thus described my invention, what I claim and desire to secure by Letters Patent is:

1. In apparatus for feeding a thread and spangles mounted thereon to a spangling machine, said spangles being carried by said thread and movable therewith and longitudinally thereof during the feeding operation, an upper ramp inclined downwardly in a direction away from the spangling machine, a lower ramp inclined downwardly toward said machine, said upper

70 ramp having its lower end positioned above and spaced longitudinally from the lower end of the lower ramp, means on said upper ramp spaced from the lower end thereof for supporting a spool of said spangle-carrying thread, said thread being movable at uniform speed downwardly on said upper ramp, as the spool is unwound, to said lower end of the upper ramp and then downwardly at the same uniform speed on said lower ramp, and means at the lower end of said upper ramp for directing the thread and the spangles carried thereby from said upper ramp to said lower ramp.

2. In apparatus for feeding a thread and spangles mounted thereon to a spangling machine, said spangles being carried by said thread and movable therewith and longitudinally thereof during the feeding operation, an upper ramp inclined downwardly in a direction away from the spangling machine, a lower ramp inclined downwardly toward said machine, said upper ramp having its lower end positioned above and spaced longitudinally from the lower end of the lower ramp, means on said upper ramp spaced from the lower end thereof for supporting a spool of said spangle-carrying thread, said thread being movable at uniform speed downwardly on said upper ramp, as the spool is unwound, to said lower end of the upper ramp and then downwardly at the same uniform speed on said lower ramp, and means at the lower end of said upper ramp for directing the thread and the spangles carried thereby from said upper ramp to said lower ramp.

3. In apparatus for feeding a thread and spangles mounted thereon to a spangling machine, said spangles being carried by said thread and movable therewith and longitudinally thereof during the feeding operation, an upper ramp inclined downwardly in a direction away from the spangling machine, a lower ramp inclined downwardly toward said machine, said upper ramp having its lower end positioned above and spaced longitudinally from the lower end of the lower ramp, means on said upper ramp spaced from the lower end thereof for supporting a spool of said spangle-carrying thread, said thread being movable at uniform speed downwardly on said upper ramp, as the spool is unwound, to said lower end of the upper ramp and then downwardly on said lower ramp, a driven roller for directing the thread and the spangles carried thereby from said upper ramp to said lower ramp for movement downwardly of said lower ramp toward the spangling machine.

4. In apparatus for feeding a thread and spangles mounted thereon to a spangling machine, said spangles being carried by said thread and movable therewith and longitudinally thereof during the feeding operation, an upper ramp inclined downwardly in a direction away from the spangling machine, a lower ramp inclined downwardly toward said machine, said upper ramp having its lower end positioned above and spaced longitudinally from the lower end of the lower ramp, means on said upper ramp spaced from the lower end thereof for supporting a spool of said spangle-carrying thread, said thread being movable at uniform speed downwardly on

said upper ramp, as the spool is unwound, to said lower end of the upper ramp and then downwardly at the same uniform speed on said lower ramp, and power driven rollers spaced from each other longitudinally of the direction of feed of the spangles and thread down the lower ramp to advance said spangles toward the spangling machine.

5. In apparatus for feeding a thread and spangles mounted thereon to a spangling machine, said spangles being carried by said thread and movable therewith and longitudinally thereof during the feeding operation, a plurality of inclined supports positioned one above the other, a lower one of said supports being inclined downwardly toward the spangling machine and an upper one of said inclined supports being inclined downwardly toward the upper part of said lower one of the supports and in a direction away from the spangling machine, means provided in the apparatus for supporting a spool of the spangle-carrying string for the unwinding thereof while the string and spangles move downwardly on said supports, and power operated means for directing the string and spangles from the lower part of the upper support to the upper part of the lower support for movement down said lower support, said thread being moved at uniform speed longitudinally of said supports.

6. In apparatus for feeding a thread and spangles mounted thereon to a spangling machine, said spangles being carried by said thread and movable therewith and longitudinally thereof during the feeding operation, a plurality of inclined supports positioned one above the other, a lower one of said supports being inclined downwardly toward the spangling machine and an upper one of said inclined supports being inclined downwardly toward the upper part of said lower one of the supports and in a direction away from the spangling machine, means provided in the apparatus for supporting a spool of the spangle-carrying string for the unwinding thereof while the string and spangles move downwardly on said supports, and a power driven roller for directing the thread and the spangles carried thereby from said upper support to said lower support for movement downwardly of said lower support toward the spangling machine, said thread being moved at uniform speed longitudinally of said supports.

7. In apparatus for feeding a thread and spangles mounted thereon to a spangling machine, said spangles being carried by said thread and movable therewith and longitudinally thereof during the feeding operation, a plurality of inclined supports positioned one above the other, a lower one of said supports being inclined downwardly toward the spangling machine and an upper one of said inclined supports being inclined downwardly toward the upper part of said lower one of the supports and in a direction away from the spangling machine, means provided in the apparatus for supporting a spool of the spangle-carrying string for the unwinding thereof while the string and spangles move downwardly on said supports, a power driven roller for moving and directing the thread and the spangles carried thereby from said upper support to said lower support for movement downwardly of said lower support toward the spangling machine, a

power driven roller at the lower part of said lower support for advancing the thread and spangles toward the spangling machine, and means for driving said rollers in unison, said thread being moved at uniform speed longitudinally of said supports.

8. Apparatus for feeding a thread and spangles mounted thereon to a spangling machine, said spangles being carried by said thread and movable therewith and longitudinally thereof during the feeding operation, said apparatus comprising a plurality of inclined supports positioned one above the other, a lower one of said supports being inclined downwardly toward the spangling machine and an upper one of said inclined supports being inclined downwardly toward the upper part of said lower one of the supports and in a direction away from the spangling machine, means provided in the apparatus for supporting a spool of the spangle-carrying string for the unwinding thereof while the string and spangles move downwardly on said supports, and power operated means spaced from each other longitudinally of the direction of feed of the spangles and thread down the lower support to advance said spangles toward the spangling machine, said thread being moved at uniform speed longitudinally of said supports.

9. Apparatus for feeding a thread and spangles mounted thereon to a spangling machine, said spangles being carried by said thread and movable therewith and longitudinally thereof during the feeding operation, said apparatus comprising a first longitudinally extending support inclined downwardly toward the spangling machine, a second longitudinally extending support positioned at a higher level than said first support and inclined downwardly in a different direction, means provided in the apparatus for supporting a spool of the spangle-carrying string for the unwinding thereof while the string and spangles move downwardly on said supports, and power operated means for directing and moving the string and spangles from the lower part of the upper support to the upper part of the lower support for movement down said lower support, said thread being moved at uniform speed longitudinally of said supports.

10. Apparatus for feeding a thread and spangles mounted thereon to a spangling machine, said spangles being carried by said thread and movable therewith and longitudinally thereof during the feeding operation, said means comprising a first longitudinally extending support inclined downwardly toward the spangling machine, a second longitudinally extending support positioned at a higher level than said first support and inclined downwardly in a different direction, means provided in the apparatus for supporting a spool of the spangle-carrying string for the unwinding thereof while the string and spangles move downwardly on said supports, and a driven roller for directing and moving the thread and the spangles carried thereby from said upper support to said lower support for movement downwardly of said lower support toward the spangling machine, said thread being moved at uniform speed longitudinally of said supports.

CHARLES WEISS.
